UNITED STATES PATENT OFFICE.

ZENSHIRO TERUYA, OF NEW YORK, N. Y.

GAME APPARATUS.

1,245,820.

Specification of Letters Patent.

Patented Nov. 6, 1917.

Application filed March 6, 1917. Serial No. 152,862.

To all whom it may concern:

Be it known that I, ZENSHIRO TERUYA, a subject of the Emperor of Japan, residing at New York city, in the county of New York and State of New York, have invented new and useful Improvements in Game Apparatus, of which the following is a specification.

This invention relates to a game apparatus designed for the playing thereon of a game somewhat similar to the well known Japanese rolling game.

The invention aims to provide a game apparatus of the above mentioned character, embodying a novel construction of means for scoring different points of the game, the general construction and arrangement of parts being such that obtaining a high score is rendered very difficult, thus adding to the interest and amusement of the player.

The nature and advantages of the invention will be better understood from the following detail description of the invention when taken in connection with the accompanying drawing, the invention residing in the construction, combination and arrangement of parts as claimed.

In the drawing forming part of this specification like numerals of reference indicate similar parts in the several views and wherein:

Figure 1 is a perspective view of my game apparatus.

Fig. 2 is a sectional view taken on line 2-2 of Fig. 1.

Fig. 3 is a sectional view through one of the pegs.

Referring more particularly to the drawing in detail, the apparatus constructed in accordance with my invention preferably embodies a playing board 10 of elongated rectangular formation, which may be supported in any suitable manner, but as shown in this specific instance is supported by means of the legs 11. The playing surface is bounded by the walls 12, while arranged adjacent the forward end of the playing board is a receptacle 13, supported in any suitable manner, and provided to hold the balls 14 employed in playing the game.

Rising from the playing surface at an appropriate point in the length thereof, but in the vicinity of the opposite end of the board, is a partition 15 which extends transversely of the board and is coextensive with the width of the latter. The partition at its

lower edge is provided with a transverse series of inverted U-shaped openings 16, defining passages or ways for the balls 14 when the latter are rolled in the direction of the partition. Journalized between the vertical walls of each opening 16 is a bladed wheel 17, the blades being preferably though not necessarily arranged in right angular relation with respect to each other, while each blade has arranged thereon indicia indicative of the value of the particular blade. The indicia on each blade of each wheel is different, whereby the respective blades each have a different scoring value, while each wheel varies in the same respect from the remaining wheels. In practice the player is given a predetermined number of balls for a predetermined sum, say for instance nine balls for ten cents, and it is the object of the player to roll the balls through one of the passages or ways defined by the openings 16, with a view of rotating the wheel journalized in the particular opening through which the ball passes, and the particular blade that presents itself within the opening when the wheel ceases to rotate, indicates by the indicia thereon the particular number of points scored with that one ball. Of course the balls are rolled in the direction of the partition singly, and when the entire set of balls has been used in this manner, the total number of points scored are added, and a prize awarded to the player, consistent with the total number of points scored.

Rising from the playing surface 10 in advance of the partition 15 is a plurality of pegs 18, disposed in staggered relation, and serving to obstruct the passage of the balls in their travel in the direction of the partition 15. Manifestly the balls are caused to pursue a zigzag course to the partition 16, and consequently the success of the player in scoring points, by having one or more of the balls pass through the openings 16 is rendered very difficult. The speed of the ball is so checked or retarded through the instrumentality of the pegs 18, that when one of the balls passes through one of the openings 16, its impact against the blade of the wheel arranged in the opening, is only sufficient to rotate the wheel enough to bring the next blade in order within the opening. The playing surface 10 adjacent certain pegs 18 is also marked with numbers, so that points of the game can also be scored with balls that have been

so retarded in their movement in the direction of the partition, that they do not pass through any of the openings 16. However it is necessary in order to score in this manner, to have the ball rest against the particular peg having a scoring value. These pegs are known as lucky pegs, and are by preference recessed as at 19 to accommodate the ball, or in other words assist the ball in obtaining a position directly thereagainst. It is therefore obvious, that I have devised a construction and arrangement of parts in the production of a game apparatus, which renders the playing of the game with a resultant high score very difficult, and which consequently materially adds to the interest of the game, and affords the player considerable amusement.

While I have shown and described what I consider the preferred embodiment of the invention, I do not limit myself to this exact construction, and that such changes may be resorted to when desired as fall within the scope of what is claimed.

What is claimed is:—

1. A game apparatus embodying a playing board, a transverse partition disposed

adjacent one end of said board and having openings therein, balls adapted to be rolled in the direction of the partition to pass through said openings, said openings having relatively high and low values, means for determining the score of such balls that pass through one of said openings, pegs rising from the board in staggered relation and in advance of the partition, and certain of said pegs having a fixed value and provided with a recess to receive a portion of the balls as and for the purpose described.

2. A game apparatus embodying a playing board, a transverse partition disposed adjacent one end of the board and having a plurality of openings therein, a biaded wheel journaled in each opening, the blades of each wheel having different scores, balls adapted to be rolled in the direction of the partition to pass through one of said openings, and to rotate said wheel, and pegs rising from said board in advance of the partition, said pegs being disposed in staggered relation.

In testimony whereof I affix my signature.

ZENSHIRO TERUYA.
